CLOTHES DRYER

Takeshi Yamamoto, Tokyo, Japan, assignor to Hitachi, Ltd.

Filed Mar. 22, 1972, Ser. No. 237,242

Term of patent 14 years

Int. Cl. D7—05

U.S. Cl. D49—1 A

FIG. 1

FIG. 2

FIG. 3

FIG.4

FIG.5

FIG.6

FIG. 1 is a right side, top and front perspective view of a clothes dryer showing my new design.

FIG. 2 is a front elevational view thereof.

FIG. 3 is a cross-sectional view, taken along line III-III of FIG. 2.

FIG. 4 is a right side, top and front perspective view of a clothes dryer showing another embodiment of my new design.

FIG. 5 is a front elevational view thereof.

FIG. 6 is a cross-sectional view taken along line VI-VI of FIG. 5.

That side of the clothes dryer not shown is substantially the same as the side which is shown and the back is substantially plain.

I claim:

The ornamental design for a clothes dryer, as shown and described.
